VENT, OVERFLOW, AND LADDER UNIT FOR
STORAGE TANKS

Robert A. Jackson, Tulsa, Okla., assignor to Chicago Bridge & Iron Company, a corporation of Illinois

Application June 5, 1946, Serial No. 674,615

15 Claims. (Cl. 137—21)

1

This invention relates to a storage tank, and relates particularly to a vent, overflow, and ladder unit for a storage tank.

In erecting large storage tanks, particularly those with elevated storage portions, it has been found desirable to include a revolving ladder as supplemental equipment. This ladder is permanently fixed to the tank, and is adapted to be revolved around the tank for the use of inspectors, painters, and other workmen. The ladder is ordinarily mounted on rollers contacting the surface of the storage portion of the tank.

Storage tanks for the storage of liquids are also ordinarily provided with vents for the escape of gas and of liquid if the tank is filled too full, or if the contents of the tank expand. I have invented a unit comprising a vent, overflow, and ladder, with the unit being capable of movement around at least a portion of the tank surface. As these objects are ordinarily mounted on the outside of the tank, it has been found desirable to reduce their bulk as much as possible, so as to give a more pleasing appearance. With the structure of the present invention the above elements are combined and can be made more cheaply and more compact. The invention comprises broadly a vent, overflow, and ladder unit comprising an overflow opening at the top of the storage portion of the tank, an overflow receptacle, a conduit attached to the receptacle and extending down the outside of the tank, a ladder associated with said conduit and rollers supporting the receptacle, conduit, and ladder against the side of the tank for movement as a unit around at least a portion of the tank surface.

The invention will be described as related to the embodiment shown in the accompanying drawings. Of the drawings Fig. 1 is an elevation of the storage portion of an elevated tank; Fig. 2 is a plan view of said tank; Fig. 3 is a fragmentary side elevation of a supporting column for the storage portion and an overflow pipe and ladder; Fig. 4 is a front elevation of the structure shown in Fig. 3; and Fig. 5 is a vertical section taken along line 5—5 of Fig. 2.

The elevated storage tank shown in the accompanying drawings comprises a storage portion 10 and spaced supporting columns 11. At the top of the storage portion 10 there is located an upwardly extending pipe 12 having an outwardly curved outer end 13. Immediately beneath this outer end 13 there is located a circular trough 14. This circular trough is mounted on a plurality of rollers 15 rolling upon a flat annular plate 16 surrounding the base of pipe 12. 55

2

The trough 14 is also provided with spaced horizontal rollers 17 contacting the pipe 12 and serving to maintain the trough 14 substantially concentric to the pipe 12.

5 The upper end 13 of the pipe 12 is provided with a cover 18 spaced therefrom. This cover 18 is hingedly mounted on an arm 19 supported from the curved outer end 13 of the pipe 12. The cover 18 is held in its spaced relationship by a plurality 10 of upwardly extending brackets 20 spaced around the upper end 13 of the pipe 12. Thus the pipe 12 serves as an overflow outlet, and the combination of the pipe 12 and the cover serves as a vent. The trough 14 has an overflow pipe 21 in communication therewith and extending down the outside of the storage portion 10. The overflow pipe 21 is supported on rollers 22 bearing against the outer surface of the storage portion 10.

15 The bottom end of the overflow pipe 21 is re-20 movably attached to a fixed pipe 23 by means of a pipe union 24, or a similar device. The fixed pipe 23 is shown adjacent a supporting column 11, although it may be in any other desired location.

25 Mounted on the overflow pipe 21 are spaced ladder rungs 25. These ladder rungs extend from the trough 14 to the pipe union 24. A fixed ladder 26 is mounted on a supporting column 11 and extends from the ground to a point beneath 30 the pipe union 24. When the two overflow pipes 21 and 23 are fastened together, as shown in the drawings, a continuous ladder will thus be provided from the ground to the trough 14. Although the fixed ladder 26 is shown mounted on 35 a column 11 by means of brackets 27, it may have any desired position so long as it is beneath the lower end of the overflow pipe 21.

When the two overflow pipes 21 and 23 are fastened together as shown any liquid within the 40 tank will flow out the upwardly extending pipe 12 into the trough 14 and down the overflow pipes 21 and 23 when the liquid within the tank expands or when the tank is filled too full. When it is desired to inspect the entire tank or to 45 paint the surface of the tank the two overflow pipes 21 and 23 may be uncoupled at the pipe union 24, and the movable pipe 21 moved around the surface of the storage portion 10 of the tank. The movable overflow pipe 21 turns on its rollers 22, and this turns the trough 14 on its rollers 15. Thus the pipe 21 and trough 14 may be turned to any desired position on the tank's surface, and painters or inspectors may use the ladder rungs 25.

Although only one movable overflow pipe 21

has been shown, it may be desired to use two overflow pipes arranged substantially parallel and closely spaced together with the ladder rungs extending between the two pipes. These two pipes could then be attachable to either one or two fixed overflow pipes 23.

Having described my invention as related to the embodiment set out in the accompanying drawings, it is my intention that the invention be not limited by any of the details of the description unless otherwise specified, but rather be construed broadly within its spirit and scope as set out in the accompanying claims.

I claim:

1. In a storage tank structure including a storage portion, an overflow and ladder unit comprising an overflow opening, an overflow receptacle, a conduit attached thereto, extending down the outside of the tank, a ladder associated with said conduit, and rollers supporting the receptacle, conduit and ladder against the side of the tank for movement as a unit around at least a portion of the tank surface.

2. The unit of claim 1 wherein the ladder comprises ladder rungs mounted on the conduit.

3. The unit of claim 1 wherein the overflow opening comprises an upstanding pipe having a flared outer end and the receptacle comprises a trough arranged beneath the flared end, and there is provided a cover over the opening spaced from the outer end thereof.

4. The unit of claim 1 wherein the conduit comprises at least one pipe depending from the receptacle and having its lower end removably attached to a fixed pipe.

5. The unit of claim 1 wherein the conduit comprises a single pipe depending from the receptacle with the ladder comprising spaced rungs attached to said pipe.

6. In a storage tank structure including a storage portion, an overflow and ladder unit comprising an upstanding overflow pipe having a flared outer end, a trough arranged beneath the flared end, at least one depending pipe communicating with the trough and extending down the outside of the tank, rollers supporting the trough and depending pipe on the outer surface of the storage portion of the tank, and spaced ladder rungs mounted on the depending pipe.

7. The unit of claim 6 wherein the storage portion of the tank is substantially circular in horizontal cross-section and the upstanding pipe is located at substantially the peak of the vertical center of the storage portion.

8. The unit of claim 6 wherein the depending pipe has its lower end removably attached to a fixed pipe.

9. The unit of claim 6 wherein the trough is provided with spaced substantially horizontal rollers contacting the upstanding overflow pipe.

10. The unit of claim 6 wherein there is provided a cover over the upper end of the upstanding pipe with the cover spaced from said end.

10 11. In a storage tank structure including a storage portion of substantially circular cross-section, a vent, overflow, and ladder unit comprising an upstanding combined overflow pipe and vent having a flared outer end and located at substantially

15 the peak of the vertical center of the storage portion, a circular trough positioned under the flared portion of said pipe, rollers supporting the trough on the storage portion for revolution around the upstanding pipe, substantially horizontal rollers between the trough and the upstanding pipe, at least one depending overflow pipe extending from the trough down along the outside of the storage portion, spaced rollers supporting the overflow pipe against the storage portion of the tank, said trough and overflow pipe being movable around the tank with the upstanding pipe serving as a center of revolution, and spaced ladder rungs mounted on the depending pipe.

30 12. The unit of claim 11 where the bottom end of the depending pipe is removably fastened to a fixed pipe.

13. The unit of claim 11 wherein the upstanding pipe is provided with a cover over its upper end with the cover being spaced from said end.

35 14. The unit of claim 11 wherein the upstanding pipe is provided with a cover over its upper end with the cover being spaced from said end, and the bottom end of the depending pipe is removably fastened to a fixed pipe.

40 15. In a storage tank structure including a storage portion, an overflow and ladder unit comprising an overflow opening, a conduit attached thereto and extending down the outside 45 of the tank, a ladder associated with said conduit, and rollers for maintaining the conduit and ladder in a position spaced from the tank, said conduit and ladder being movable as a unit by means of said rollers around at least a portion of the tank surface.
